UNITED STATES PATENT OFFICE.

JAMES FULTON, OF GREAT BEND, NEW YORK, ASSIGNOR TO HASKEL B. FULTON, OF SAME PLACE.

MOWING-MACHINE SEAT.

SPECIFICATION forming part of Letters Patent No. 254,300, dated February 28, 1882.

Application filed July 22, 1881. (No model.)

To all whom it may concern:

Be it known that I, JAMES FULTON, of Great Bend, in the county of Jefferson and State of New York, have invented certain new and useful Improvements in Mowing-Machine Seats, of which the following is a specification.

The object of my invention is such construction and attachment of the seat to the seat-standard of mowing, reaping, and similar machines that the sudden lateral motion given to the seat-standard while passing over rough and uneven ground will not be communicated to the rider, thus relieving the machine and rider of the severe strain and jolting due to such motion.

The invention consists principally of supporting the seat upon links suspended from the ends of suitable projections or arms of the seat-standard, whereby the seat is made an oscillating one in any direction.

In the accompanying drawings, Figure 1 is a side elevation of my improved mowing-machine seat. Fig. 2 is a rear elevation, and Fig. 3 is a bottom view, of the same.

Similar letters of reference indicate corresponding parts.

In the drawings, A represents the seat-standard, which may or may not be of spring material. The upper end of it is preferably bifurcated, as shown, and to the ends of the parts *a a* thereof are suspended the links *c c*.

To the under side of the seat B is secured the support D, which is formed with the lateral spring-arms *d d*, which rest in and are secured around the links *c c*. The forward

part of the seat is connected to the standard below the bifurcation by the linked tie or support *b*, which prevents the tipping of the seat too far back. Thus constructed, the seat-standard is free to move from side to side with the up-and-down movement of the axle of the machine without suddenly carrying the weight of the rider with it, which is a relief to the rider and the machine.

It is obvious that various constructions for suspending the seat might be devised and not depart from the spirit of my invention. The means shown and described for suspending the seat are, however, the preferred means.

Having thus fully described my invention, I claim as new and desire to secure by Letters Patent—

1. The combination, with the standard A and seat B, of the support D and links *c*, substantially as and for the purpose set forth. 55

2. The combination, with the standard A, provided with the bifurcations *a* and the seat B, of the support D, provided with the lateral arms *d*, and the links *c*, substantially as and for the purpose set forth. 60

3. The combination, with the standard A, provided with bifurcations *a* and the seat B, of the support D, provided with the arms *d*, the links *c*, and the linked tie *b*, substantially as and for the purpose set forth.

JAMES FULTON.
